HYGROMETER

Harry Y. Norwood, Rush, and Everett E. Newell,
Rochester, N. Y., assignors to Taylor Instrument Companies, Rochester, N. Y., a corporation of New York

Application June 6, 1932, Serial No. 615,528

2 Claims. (Cl. 73—24)

The invention relates to hygrometers. In hygrometers of one type, it has been the practice to utilize the expansion and contraction along one dimension only of a hygroscopic element 5 formed of any one of several materials such as hair, strips of paper, wood and the like, to give an indication of the prevailing relative humidity. Where such change in one dimension only of the material is relied upon to give an indication of 10 moisture conditions, the resulting instrument has necessarily been relatively bulky as well as comparatively complicated and expensive to manufacture.

In accordance with the present invention, it 15 is proposed to provide a device which utilizes the resultant of the combined changes in two dimensions of a hygroscopic member, to give an indication of the existing relative humidity. This and other features of the invention will 20 appear from the detailed description and claims, when taken with the drawing in which Fig. 1 is a side elevation of a hygrometer of the present invention with certain parts thereof broken away; and Fig. 2 is a side elevation of the hygroscopic element showing the manner in which it is mounted.

In the drawing, 5 designates a support of any 25 suitable material on which there is mounted in spaced relation thereto as by bolt 7, spacer 8 and 30 the nut 9, a hygroscopic member 6. This member may be formed of any material, the dimensions of which change in response to the amount of moisture which it absorbs or gives off. However, a suitable hygroscopic member may 35 consist of a piece of wood in the form of a disc with the principal faces thereof at right angles to the grain 6a of the wood of which it is formed. At the point 10, a band 11 is fastened to the disc and is wrapped about substantially the whole 40 periphery of the disc to respond to the changes in dimensions tangentially and radially of the grain thereof. The free end of the band may be connected to any mechanism which will indi-

cate its movement, but as herein shown, the free end of the band 11 is connected through an adjustable link 12 to the end of the segment gear arm 13. This arm is pivoted at 14 and its free end is provided with a segment gear 15 which 60 engages a gear 16 fixed on a rotatable arbor 17. There is mounted on the arbor 17, an indicator 18 which swings over the graduated scale on the dial 21, a fragment of which only is shown. A hair spring, the detailed mounting of 65 which is not illustrated, tends to move the indicator 18 clockwise as the material of the disc expands. While it is not essential to the invention, it is preferred to protect both faces of the disc 6 by perforated plates 20, also mounted on 70 bolt 7, which plates are slightly separated from the respective faces of the disc by means of washers.

While the hygroscopic member has been disclosed herein as being circular in form, the invention is not so limited but instead, this member may be made according to various geometric forms wherein the resultant of the changes in 75 two dimensions is utilized to give an indication of changing moisture conditions. 80

We claim:

1. In a device of the class described, a member of hygroscopic material fixed against rotation, said member having a relatively large cross-sectional area, a flexible element connected at one 85 end to said member and engaging a portion of the periphery thereof, and indicating means arranged to be actuated by the movement of the free end of said element.

2. In a device of the class described, a hygroscopic member having a substantial cross-sectional area, a flexible strip having one end fixed, said strip being wrapped about a substantial portion of the perimeter of said area, and an indicating member actuated by the free end of said 95 strip.

HARRY Y. NORWOOD.
